ADAPTER FOR DRAFT REGULATORS

Filed April 6, 1933

UNITED STATES PATENT OFFICE

1,980,818

ADAPTER FOR DRAFT REGULATORS

Clarence H. Morrow, Shaker Heights, Ohio, assignor to The Hotstream Heater Company, Cleveland, Ohio, a corporation of Ohio

Application April 6, 1933, Serial No. 664,792

5 Claims. (Cl. 285—105)

This invention relates to means for mounting a draft regulator, such as that shown in my Patent No. 1,905,734, on the breaching of the stack whose draft is to be controlled. Such mounting includes a cylindrical thimble, extending from the breaching to support the regulator itself somewhat spaced from the breaching itself; and the invention has for its object the provision of means for accomplishing such a mounting wherein the diameter of the thimble is substantially the transverse dimension of the breaching, whether the breaching be of cylindrical or rectangular type. Other objects of the invention are to provide for convenience in accomplishing the installation, and particularly to provide that in the assembly the breaching shall not be weakened.

The exact nature of this invention together with further objects and advantages thereof will be apparent from the following description taken in connection with the accompanying drawing, in which Fig. 1 is a perspective view of an embodiment of the invention as applied to a square breaching; Figs. 2 and 3 are enlarged details in section, longitudinal and transverse respectively of the thimble and associated parts, the section of Fig. 2 being indicated by the line 2—2, Fig. 3, and that of Fig. 3 being indicated by the line 3—3, Fig. 2; Figs. 4, 5 and 6 are views illustrating the invention as applied to a round breaching, the views corresponding generally to Figs. 1, 2 and 3 respectively, the section of Fig. 6 being that of the line 6—6, Fig. 5, and the section of Fig. 5 being in the central plane of the parts appearing Fig. 6.

With reference now to the disclosure of Figs. 1—3, 1 is the base part and 2 the damper part of the draft regulator, the details of which are immaterial here but which may be as illustrated and described in my Patent No. 1,905,734. 3 represents a horizontal rectangular breaching to the side face 4 of which the draft regulator is to be applied, supported in spaced relation from the breaching by a thimble ring 5, the thimble ring being secured with the breaching by a base casting 6 which includes features of the invention as will appear.

It will be noted that the size of the draft regulator is substantially that of the breaching, so that the diameter of the thimble ring 5 is substantially the same as the transverse dimension of the breaching side 4. Hence the mere cutting of a circular opening in the breaching side, to fit the thimble ring, would greatly reduce the strength of the breaching.

The base 6 of the thimble assembly is prefer-

ably of cast metal, of generally annular form. It has an annular flange part 7 outstanding from the breaching to receive and position the thimble ring as shown Fig. 2 and a flange part adapted to bear against the breaching, extending inwardly of the flange part 7 as at 8 and outwardly of the flange part 7 as at 9, with ears 10 by which it may be bolted to the breaching as indicated at 11.

That the thimble ring may be secured in its position fitting over the base flange 7, after the base is mounted on the breaching, bolt-receiving bosses 12 are provided in the flange 9 with bolt-receiving slot openings 13 as shown Fig. 3, and each boss is recessed as at 14, Fig. 2, to receive the head of a bolt in its slot 13, clear the head from the near face of the breaching, and fit the head to prevent turning of the bolt. The thimble ring 5 is provided with angle brackets 15 each secured with the ring as by a bolt 16 and positioned thereon to register with one of the bosses 12. A bolt 17 serves to secure each bracket 15 with the base 6, by insertion into the corresponding slot 13 as shown in the drawing.

At opposite sides of the base 6 the inner flange part 8 is extended inwardly to form a pair of oppositely disposed webs 18. Thus while the typical section through the base 6 is of T characteristic as indicated at the top of Fig. 2, at the webs 18 the typical section is of L characteristic as indicated at the bottom of Fig. 2.

In practice, to mount the draft regulator upon the breaching the base ring 6 is first placed against the breaching, with the base so disposed that the webs 18 will lie adjacent the edges. The breaching is then marked through the openings in the ears 10 for holes to receive the bolts 11. The base is then removed, the breaching drilled to receive the bolts and the base replaced and positioned by the bolts. Then, using the base as a templet, the breaching opening is cut, following the outline of the flange 8, the base again being used as a templet. As the opening is made in the breaching, it is reinforced by the base, so that it is not materially weakened. After the opening is completed, nuts are turned onto the bolts 11 and the bolts tightened. The side of the breaching now has an opening substantially circular and of diameter substantially as great as the breaching side, yet the breaching is so reinforced by the base 6 and particularly by the flange webs 18 that the breaching as a whole is as strong as before.

The thimble ring 5 is next positioned over the flange 7 of the base and there secured as by bolts 17 inserted in the bosses 12. The draft regulator

assembly is then mounted on the end of the thimble ring in the usual manner.

With reference now to the embodiment of Figs. 4-6, where the breaching 3a is cylindrical, and of the same diameter as the thimble ring 5a, the base for mounting the ring on the breaching is in two pieces 6a and 6b. These pieces are identical castings, flanged as at 20 to receive bolts 21 whereby they are secured together to form a short cylindrical section terminating at one end in a transverse plane and at the other end to fit the breaching, with an outstanding flange 22 overlying the breaching. The flange 22 is provided with openings to receive bolts 23 whereby the base assembly may be secured to the breaching and the pointed extremities of the assembly lying on opposite sides of the breaching are provided with openings to receive a stay bolt 24 extending across through the hollow of the breaching generally diametrically thereof. The stay bolt is provided with nuts 25 within the breaching and nuts 26 outside the breaching, and is threaded at its ends sufficiently to allow enough inward adjustment of the nuts 25 that the stay bolt may be inserted.

At its outer extremity the base assembly has a peripheral flange 9a and longitudinally extending flange 7a to receive and position the thimble ring 5a. The flange 9a having simple ears 27 to receive bolts 17a by which the thimble ring, bracketed at 15a as before, may be secured to the base assembly in the same general manner as in the embodiment of Figs. 1-3. The draft regulator 1a with its damper 2a is mounted on the thimble ring 5a as before.

The mounting operations are also generally as before. The base assembly is first made by bolting the base parts 6a and 6b together by bolts 21. The assembly is next placed on the breaching in proper position and used as a templet in marking the breaching for holes to receive the bolts 23 and the stay bolt 24. The base is then removed and the breaching drilled for these bolts after which the base is replaced and there secured by insertion of the bolts 23 and insertion of temporary short bolts in the holes for the stay bolt 24. The opening is next cut in the breaching using the base as a templet, after which nuts are placed on the bolts 23 and the stay bolt 24 inserted, working through the opening. All of these bolts then being tightened, the thimble ring and draft regulator are mounted as before.

It will be appreciated that in either form of the device the manner of cutting the necessary opening in the breaching will depend upon the material of the breaching. Thus if of metal, a torch may be used. While in either case the opening may be cut after mounting of the base upon the breaching to reinforce the latter, if the breaching have sufficient external support, of course, the opening may be cut before mounting the base, the opening having been laid out with a marker using the base as a templet.

What I claim is:

65. 1. In a device of the class described for mount-

ing a draft regulator on a stack breaching of substantially commensurate size, a base having a flange adapted to overlie a side of said breaching with openings for bolting to the latter, and having a circular flange adapted to receive and position a draft-regulator-supporting thimble, said base having means outside said circular flange adapted to receive and position thimble-securing bolts from without said breaching after mounting the base on the breaching, and to secure the heads of said bolts against turning. 85

2. In a device of the class described for mounting a draft regulator on a stack breaching of substantially commensurate size, a base having laterally extending flange parts adapted to overlie a side of said breaching with openings for bolting to the latter, a thimble receiving flange part adapted to position a draft-regulator-supporting thimble extending from said breaching side, and opposed flanged parts extending inwardly from said thimble-receiving flange to reinforce said base adjacent the edges of said breaching part. 90

3. A device of the class described for mounting a cylindrical draft regulator thimble on the side of a rectangular stack breaching, the thimble diameter being substantially equal to the width of said breaching side, said device comprising a generally annular base having a flange part arranged to extend from said breaching to receive and position said thimble, said base having a pair of inwardly extending webs oppositely disposed to reinforce said breaching adjacent the edges of said breaching side. 100

4. In a device of the class described for mounting a draft-regulator-supporting thimble on a stack breaching, said parts being cylindrical and of substantially equal diameters, a base adapted to fit against a side of said breaching and be secured thereto for service as a templet in cutting an opening in said breaching side, said base having a flange with openings for bolting to the breaching, a stay bolt arranged to extend diametrically across the passageway in said breaching, between the extremities of said base on opposite sides of the breaching, said base having a part extending from the breaching to receive and position said thimble. 110

5. In a device of the class described for mounting a draft-regulator-supporting thimble on a stack breaching, said parts being cylindrical and of substantially equal diameters, a base adapted to fit against a side of said breaching and be secured thereto for service as a templet in cutting an opening in said breaching side, said base having a flange with openings for bolting to the breaching, a stay bolt arranged to extend diametrically across the passageway in said breaching, between the extremities of said base on opposite sides of the breaching, said base having a part extending from the breaching to receive and position said thimble, said base comprising a pair of similar parts joined by bolt means including said stay bolt. 125
